UNITED STATES PATENT OFFICE.

CHARLES BURRIER, OF MIDDLETOWN, PENNSYLVANIA, ASSIGNOR TO UNITED SHOE MACHINERY CORPORATION, OF PATERSON, NEW JERSEY, A CORPORATION OF NEW JERSEY.

HORN FOR SEWING MACHINES.

Application filed August 13, 1921. Serial No. 491,909.

This invention relates to shoe sewing machines and more particularly to a work supporting horn for shoe sewing machines.

In shoe sewing machines of the well-known McKay type, the work is supported during the sewing operations upon a horn extended within the shoe. Heretofore, such work supporting horns have been provided with a guard between which and the body 10 of the horn the thread passes to the usual whirl located in the tip of the horn. Such guards have been made of a single piece of metal and serve the purpose of protecting the lining of the shoe from the wax thread 15 as the latter is drawn through the whirl during the sewing operation. In the event of thread breakage considerable inconvenience and delay has been heretofore encountered in reaching the broken end of a thread between the guard and the body portion in 20 order to re-thread the whirl, and usually in such instances the usual practice has been to pry open the tip of the guard with a screw driver or other implement. This procedure resulted oftentimes in breaking off 25 the tip of the guard, thereafter exposing the shoe lining to the wax thread.

The object of the present invention is to provide an improved horn for sewing machines in which in the event of thread breakage, ready access may be had to the end of the thread between the horn guard and the body portion of the horn, so that the whirl may be readily re-threaded, thus eliminating 35 the breakage of the tips of the horn guards.

To this end the invention consists in the work supporting horn for sewing machines hereinafter described and claimed.

40 In the accompanying drawings illustrating the preferred embodiment of the invention Fig. 1 is a vertical section of the improved horn; and Fig. 2 is a front elevation of the horn guard.

45 The improved horn illustrated in the drawing comprises the usual upwardly curved body portion 1 which is secured to the usual base not shown, in position to enter the shoe and support it during the sewing operation. The body portion 1 is provided with a whirl 4 in the upper end portion thereof of the usual construction, driven from the cam shaft of the sewing machine in the usual manner through a

55 pinion 6 on the upper end of an inclined shaft 8, itself driven from a vertical shaft 10 by cooperating gears 12 and 14.

The body portion 1 of the horn is provided with a guard 20 for protecting the lining of the shoe from the wax thread as the latter passes upwardly between the guard and the body portion 1 of the horn on its way to the whirl 4. In order to afford ready access to the thread between the guard and body portion so that in event of thread breakage the operator may quickly and conveniently reach the end of the broken thread to re-thread the whirl, provision is made for permitting a portion of the guard to be swung outwardly from the body portion of the guard. For this purpose the guard 20 is made in two parts, a lower part 24 rigidly secured to the body portion 1 by screws 26 and an upper or tip portion 28 pivoted upon the upper end of the lower or stationary portion 24. The tip or upper portion 28 of the guard is provided with a tongue 29 which fits into a corresponding groove 31 in the lower or stationary portion 28 of the guard, as shown in Fig. 2. A pivotal pin 33 extends through the tongue 29 so that the tip or upper portion 28 of the guard is capable of pivotal movement outwardly about the pin 33 as a center. A spring 35 secured by screws 36 to the face 85 of the lower or stationary portion 24 of the guard, bears against the upper or tip portion 28 thereof to yieldingly hold the latter in an operative position, as shown in Fig. 1, and to permit the tip or upper portion of the guard to be conveniently and easily swung outwardly.

90 The thread as it comes from the usual wax pot, not shown, passes between the guard 20 and the body portion 1 of the horn, entering through an eye 40 formed in a support 42 secured by screws 44 to the under face of the guard, as shown in Fig. 1. The thread is led around a guide pulley 46 journaled in the support 42 and thence over a 95 second guide pulley 48 journaled in the upper end of the stationary portion of the guard and thence under the tip of the guard to the whirl 4.

100 From the foregoing description of the construction of the improved horn it will be apparent that in the event that the thread breaks access is afforded to the broken end

of the thread by swinging the tip or upper portion of the guard outwardly. The operator may then conveniently re-thread the whirl, and thereafter the tip of the guard is 5 yieldingly returned to an operative position by the leaf spring 35. In this manner the necessity for prying open the guard tip with a screw driver, and the breaking of the tip, are eliminated, so that the machine may be 10 restored to operation, in the event of thread breakage, with a minimum delay.

While the preferred form of the invention contemplates the pivotal and yielding mounting of the upper or tip portion of the guard, it is to be understood that viewed 15 in its broader aspects the invention contemplates any construction of horn in which one portion of the horn guard may be swung outwardly to afford the desired access to the 20 end of a broken thread.

Having thus described the invention what is claimed is:

1. A work supporting horn for sewing 25 machines of the McKay type having a body portion provided with a whirl, and a horn guard removably secured to the horn extending longitudinally of the horn between which and the body portion of the horn the thread passes to the whirl, the horn guard having 30 provision whereby the tip portion thereof

may be swung outwardly with relation to the rest of the guard to afford ready access to the end of a broken thread thereunder.

2. A work supporting horn for sewing 35 machines of the McKay type having, in combination, a body portion provided with a whirl, and a horn guard removably secured to the horn extending longitudinally of the horn between which and the body portion of the horn the thread passes to the whirl, the upper portion of the horn guard being pivoted to the lower portion of the guard to enable it to be swung outwardly to afford 40 access to the end of a broken thread thereunder.

3. A work supporting horn for sewing 45 machines of the McKay type having a body portion provided with a whirl, a horn guard extending longitudinally of the horn under which the thread passes to the whirl, comprising a lower portion removably secured to the body portion of the horn, an upper portion pivoted to the lower portion, and a spring for yieldingly maintaining the upper portion in an operative position and for 50 permitting the upper portion to be swung outwardly to afford access to a broken thread thereunder.

CHAS. BURRIER.
